(57) **CLAIM**

The ornamental design for a display structure, as shown and described.

DESCRIPTION

FIG. 1 is a first perspective view of a first embodiment of the display structure of our new design;

FIG. 2 is a second perspective view of the display structure of FIG. 1;

FIG. 3 is a front elevation view of the display structure of FIG. 1;

FIG. 4 is a rear elevation view of the display structure of FIG. 1;

FIG. 5 is a top plan view of the display structure of FIG. 1;

FIG. 6 is a bottom plan view of the display structure of FIG. 1;

FIG. 7 is a right side elevation view of the display structure of FIG. 1;

FIG. 8 is a left side elevation view of the display structure of FIG. 1;

FIG. 9 is a first perspective view of a second embodiment of the display structure of our new design;

FIG. 10 is a second perspective view of the display structure of FIG. 9;

FIG. 11 is a front elevation view of the display structure of FIG. 9;

FIG. 12 is a rear elevation view of the display structure of FIG. 9;

FIG. 13 is a top plan view of the display structure of FIG. 9;

FIG. 14 is a bottom plan view of the display structure of FIG. 9;

FIG. 15 is a right side elevation view of the display structure of FIG. 9; and,

FIG. 16 is a left side elevation view of the display structure of FIG. 9.

The broken lines in the figures show portions of the display structure that form no part of the claimed design.

1 Claim, 12 Drawing Sheets
